US0D1063694S

(12) **United States Design Patent** (10) **Patent No.:** **US D1,063,694 S**
O'Molony (45) **Date of Patent:** ** *Feb. 25, 2025

(54) **TRIBAR SLIDER**

(71) **Applicant:** **FULLBEAUTY BRANDS OPERATIONS, LLC**, Indianapolis, IN (US)

(72) **Inventor:** **Kearnon O'Molony**, New York, NY (US)

(73) **Assignee:** **FULLBEAUTY BRANDS OPERATIONS, LLC**, Indianapolis, IN (US)

(*) **Notice:** This patent is subject to a terminal disclaimer.

(**) **Term:** **15 Years**

(21) **Appl. No.:** **29/927,469**

(22) **Filed:** **Feb. 5, 2024**

Related U.S. Application Data

(63) Continuation of application No. 29/703,565, filed on Aug. 28, 2019, now Pat. No. Des. 1,017,460.

(57) **CLAIM**

The ornamental design for a tribar slider, as shown and described.

DESCRIPTION

FIG. 1 is a perspective view of a tribar slider illustrating my new design;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

(Continued)

Broken lines illustrate portions of the tribar slider that form no part of the claimed design.

1 Claim, 5 Drawing Sheets
